Alfred Robinson, Inventor

By H. Woodward, Attorney

UNITED STATES PATENT OFFICE.

ALFRED ROBINSON, OF GARDNER, MASSACHUSETTS.

FASTENER DEVICE.

Application filed March 7, 1922. Serial No. 421,770.

To all whom it may concern:

Be it known that I, ALFRED ROBINSON, a citizen of the United States, residing at Gardner, in the county of Worcester and State of Massachusetts, have invented certain new and useful Improvements in Fastener Devices, of which the following is a specification.

The invention has for an object to provide a tying device which may be made in various sizes, so that, in the same form, it may be used for many various uses, requiring only that its size may be in proportion to the strains to which it will be subjected in use. It is a particular purpose of the invention to provide a device which may be used for tightening clothes lines, securing tent ropes, fastening cords upon packages, and which may also be used as a cleat for securing rope ends, and for general uses. It is an advantage of the invention that certain eyes having special utility for guiding a cord or rope when the device is used as a package tie or line carrying fastener for rope ends, may be utilized to receive fastenings such as screws, for mounting the device upon a frame work in case it is to be used as an ordinary cleat.

It is also a special object of the invention to provide an appliance for use in hanging clothes lines or the like, which will obviate the necessity of passing the line around a hook or other support, whereby it might be chafed, thus limiting liability of breakage of the line. Additional objects, advantages and features of invention reside in the device, as may be understood from the following description and the drawings, wherein.

Fig. 1 is a perspective view of the device in use as a fastening and tension adjusting device for a clothes line.

Fig. 2 is an enlarged top view of the device.

Fig. 3 is an enlarged side elevation thereof.

Fig. 4 is an end view thereof.

Fig. 5 shows my device in use as a package tie.

There is illustrated a fastener or tie device 10 formed integrally of one piece of wire which at its central part has an eye 11 formed therein, the end portions 12 of the wire being extended rectilinearly therefrom as nearly in line with each other as practicable. The ends are looped as at 13, at a suitable distance from the eye 11 and the outer parts of the wire extended inwardly

as at 14 close beside the parts 12, the bights of the loops being as nearly circular in form as practicable, to readily accommodate twine or rope slidably therein, as may be required. The loops 13 and parts 12 and 14 are formed as nearly in the same plane with the eye 11 as practicable. The parts 14 are also laid at the same side of the device, so that they will aline as nearly as practicable, and the eye 11 is thus projected on the opposite side of the device from these parts. Adjacent the middle of the device, the extremities of the wire are bent at 15 in the same direction in a plane at right angles to that mentioned, upwardly and outwardly in a longitudinal direction at an acute angle to the parts 14, and their extremities slightly curved upward, so as to form a pair of cleat arms 16. These arms with the parts 14 form wedge slots 17 by which the ends of twine or rope may be secured, according to the size of the device. The length of the appliance, the distance between the bends 15, and the length of the arms 16 may be so proportioned that a considerable amount of twine or rope may be wound in the opposed slots 17 if desired, the device being then adapted to function as a floating cleat, or it may be mounted upon a support by means of usual screw fastenings engaged through the eye 11 and loops 13.

The appliance has been made in wire having a cross sectional diameter of one-eighth of an inch, for use upon cordage such as that generally used for clothes lines, awnings of small windows, and for tying bales and for other uses; and for tying small bundles or where twine is to be employed, it is preferably made of very small size. It may also be made of quarter-inch rod, or heavier bar material for use with large rope or cable.

In use, when employing the device to hang a clothes line (see Fig. 1) or to anchor a twine, rope, or cable, the line is inserted through one of the loops 13 and then through the eye 11, after which the remaining loop may be engaged upon a hook, spike or pin, and the short end of the line drawn upon to tighten the suspended line to the extent desired. When sufficiently taut, while maintaining sufficient tension upon the loose end, it is swung in the direction of the adjacent slot 17 until properly engaged therein, after which it is drawn toward the anchorage and engaged in the other slot 17 snugly, as shown.

In case the device is to be used for a package tie it is possible to use it without making any knots whatever, although in Fig. 5, showing a package, the ends of the twine 5 are knotted to prevent unravelling. In this instance, one end of the twine is engaged in a slot 17, and by making a turn or two around the arm 16 this initial anchorage of the twine is made more secure, preventing 10 the end from being knocked out of the slot by objects which may engage it. The twine is then extended through the loop 18 at the opposite or far end of the tie, which is next laid longitudinally upon one side of the 15 package while the twine is wrapped one or more times longitudinally therearound. The twine may next be inserted through the remaining loop 18 and carried thence through the eye 11, after which the twine is extended 20 laterally outward and wrapped transversely around the package as often as need be. The twine may then be laid in the same slot 17 in which the end was first secured and drawn into the next slot 17 for final secure- 25 ment. Wrapping it one or more times around the adjacent arm 16 and then tucking the twine end under the bindings may add to its security, preventing the end from being knocked out of the slot in the course of ship- 30 ment of the package.

In securing tent ropes and other similar uses, the tie may be engaged upon the intermediate part of the rope by inserting the rope through a loop 18, then through the 35 other loop, and next under the rope extending between the loops, whereby it will be pre-

vented from sliding upon the rope. The outer part of the rope may then be looped around a peg or snubber, drawn taut then moved into the outer slot 17 and finally 40 wrapped in the two slots as desired. Or, before being looped around the peg or snubber, the rope may have its extreme outer part passed through the eye 11 slidably, forming a loop in the intermediate end portion of 45 the rope which may be engaged with a peg or snubber. As the outer side of the loop is drawn taut, the slack may be taken up by pulling the loose end through the eye; and when drawn snug, the loose end may be secured in the slot 17 as indicated. When a rope is to be anchored to a tree or prop, it may be passed around the anchorage before being inserted through the eye 11 as last mentioned. 55

What is claimed:—

A tie device of the character indicated comprising a single piece of wire having a coil eye centrally thereof, the end parts of the wire being extended a distance in opposite directions and formed with loops, the outer parts of the wire being laid close against the parts between the eye and loops, the ends being bent laterally from the plane of the eye and acutely outward to form 60 wedge slots and cleat arms. 65

In testimony whereof I have affixed my signature in presence of two witnesses.

ALFRED ROBINSON.

Witnesses:

A. H. NOURSE,
GERTRUDE M. DWYER.
